DESIGN FOR A CAKE SOAP DRAINER TRAY OR SIMILAR ARTICLE

William H. Barg, Los Angeles, Calif.

Application January 19, 1948, Serial No. 143,889

Term of patent 14 years

(Cl. D4—3)

To all whom it may concern:

Be it known that I, William H. Barg, a citizen of the United States, residing at Los Angeles, in the county of Los Angeles and State of California, have invented a new, original, and ornamental Design for a Cake Soap Drainer Tray or Similar Article, of which the following is a specification, reference being had to the accompanying drawing, forming part thereof.

In the drawing:

Fig. 1 is a perspective view of a cake soap drainer tray, embodying my new design;

Fig. 2 is a plan view;

Fig. 3 is an end elevation view;

Fig. 4 is a side elevation view; and

Fig. 5 is a bottom view thereof.

I claim:

The ornamental design for a cake soap drainer tray or similar article, as shown.

WILLIAM H. BARG.
